ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-WRITER MARGIN-RELEASE.

1,222,328.

Specification of Letters Patent.

Patented Apr. 10, 1917.

Application filed October 19, 1914. Serial No. 867,318.

To all whom it may concern:

Be it known that I, ALVAH C. ROEBUCK, a citizen of the United States, residing at Woodstock, in the county of McHenry and State of Illinois, have invented certain new and useful Improvements in Type-Writer Margin-Releases, of which the following is a specification.

This invention relates to a typewriter margin stop and more particularly to a releasable margin stop located to control the left-hand margin, and is constructed so that it may be quickly released when it is desired to write marginal notes on the left-hand side of the sheet, without losing the adjustment of the margin stop as set for the regular margin. The principal object of the invention is to provide a new and improved construction for accomplishing this result.

For the attainment of these ends and the accomplishment of other new and useful objects as will appear, the invention consists in the features of novelty in the construction, combination and arrangement of the several parts generally shown in the accompanying drawing and described in the specification, but more particularly pointed out in the appended claims.

In the drawings, Figure 1 is a view of certain parts of a typewriting machine, some of which are broken away, illustrating the application of the present invention thereto. Fig. 2 is a view in elevation of a left-hand margin stop constructed in accordance with the principles of the invention and in engagement with a fixed stop on the frame; and Fig. 3 is a sectional view taken on the line 3—3 of Fig. 2.

While left-hand margin stops are not new, the novelty in this margin stop lies in its simplicity and its very rigid form of construction which is important because of the impact against this part each time the carriage is returned to the beginning of the line. It is difficult to make economically a stop of this kind sufficiently rigid to withstand successive impacts and at the same time render it possible to quickly release the stop at any desired time without losing the adjustment of the margin stop itself, especially when the margin stop body is movable.

Referring now more particularly to the drawing, the numeral 5 designates generally

a typewriter frame in which a carriage is transversely movable, the carriage being here represented only in part and that part designated by the reference numeral 6. Secured to the carriage is a bar 7 provided with teeth 8 at the sides, upon which a margin stop is movable with means for holding it adjustably in connection with the bar 7.

In its preferred form, the margin stop comprises a housing or body 9 which is freely movable along the bar 7, and pivoted on the body 9 is a lever 10 having a forked end 11 for engaging the teeth 8 at the sides of the bar 7, and with a knob 12 at the other end of the lever by means of which the forked end 11 may be released from engagement with the teeth. A spring 13 is disposed between the body 9 and the knob end of the lever which tends to hold the forked end of the lever in engagement with the teeth of the bar 7. Extending from both sides of the body 9 are pivots 14 on which is mounted a release lever 15 having an arm 16 which extends above the body of the stop for manual operation. The other arm of the lever 15 comprises an engaging portion 17 and an angular abutment 18. To accommodate this angular abutment, the lower portion of the body 9 is formed with an angular notch 19 in which the abutment 18 is adapted to engage. Disposed between the body 9 and the engaging portion 17, is a spring 20 which tends to press the engaging portion away from the body and to seat the angular abutment 18 in the notch 19. When the abutment is in the notch, no further movement of the lever in the outward direction is possible. By compressing the spring 20, however, either by pressing the arm 16 of the lever, or in any other suitable way, the engaging arm 17 of the lever may be moved in the direction of the body 9, thereby unseating the abutment 18 from its notch 19.

Secured to the frame 5 of the typewriting machine in the path of the engaging portion 17 of the lever 15, is a bracket 21 provided with an upturned end and sides 22 which forms a pocket for receiving the engaging end 17 of the lever. The top of this bracket is spaced from the lower part of the body portion 9 of the margin stop so that when the releasing lever is moved upwardly to the dotted position shown in Fig. 2, the margin stop can be moved past the stop bracket 21.

21, and consequently the carriage to which the bar 7 is attached may be moved in this direction, permitting an operator to write on the left-hand side of the margin determined by the margin stop, without losing the permanent adjustment of the margin stop.

With this construction, it will be seen that the impact of the engaging arm with the stop bracket is not communicated directly to the pivots 14 of the releasing lever, but is communicated to the body 9 of the stop which is held firmly in position by means of the forked end of the lever 10, since the abutment 18 is normally in engagement with its angular notch 19. Thus the pivots 14 are relieved of the strain due to the successive impacts of the margin stop with the stop bracket. The stop bracket itself is strengthened by reason of the upturned sides which form a pocket for receiving the engaging end of the lever 15.

What I claim is:

1. In a typewriter, the combination with a frame and a movable carriage, of a fixed stop in connection with the frame, and an adjustable margin stop in connection with the carriage, having a releasable lever pivoted on the margin stop and formed with an abutment to engage the fixed stop and movable out of engaging position to permit writing in the margin without losing the adjustment of the margin stop.

2. In a typewriter, the combination with a movable rack bar, of a frame with respect to which the rack bar is movable, a fixed stop in connection with the frame, and a margin stop adjustable on the rack bar comprising a body portion with an angular notch, and a lever pivoted to the body having an arm with an abutment to engage in the notch and to engage the stop on the frame.

3. In a typewriter, the combination with a movable rack bar, of a frame with respect to which the rack bar is movable, a fixed stop in connection with the frame, and a margin stop adjustable on the rack bar comprising a body portion with an angular notch and a lever pivoted to the body having an arm for engaging the stop on the frame and formed with an abutment to engage in the notch and rotatable out of position to engage the fixed stop on the frame.

4. In a typewriter, the combination with a frame and a movable rack bar, of a releasable margin stop having means for adjusting its position with respect to the rack bar and having a pivoted lever formed with an abutment which engages the stop and limits the movement of the lever in a direction away from the stop, and a fixed stop in connection with the frame for engaging the lever to limit the movement of the rack bar.

5. A typewriter margin stop with means

for adjusting the position of the stop and comprising a body portion with an angular notch, and a releasing lever pivoted to the body with an arm extending therefrom and formed with an angular abutment adapted to engage in the notch whereby the impact of the stop will be communicated directly to the body of the stop and not to the pivots of the lever.

6. A typewriter margin stop comprising a body portion with means for adjusting the position of the stop and with an angular notch in the outer surface of the body portion, and a releasing lever for the stop pivoted to the body portion and having an arm movable toward and from the body with an abutment to engage the notch in the body to limit the outward movement of the arm, constituting a rigid contact arm for communicating an impact therewith directly to the body portion.

7. A typewriter margin stop comprising a body portion with means for adjusting the position of the stop and with an angular notch in the outer surface of the body portion, and a releasing lever for the stop pivoted to the body portion having an arm movable toward and from the body with an abutment to engage the notch in the body to limit the outward movement of the arm, and a spring tending to press the arm outwardly from the body portion.

8. A releasable typewriter margin stop comprising a body portion with means for adjusting and holding it in any adjusted position and with an angular notch in the surface of the body, of a lever pivotally connected to the body, having an arm extending above the body and another arm constituting the contact member of the stop formed with an angular abutment adapted to engage in the notch to limit the movement of the stop arm away from the body, and a spring tending to press this arm in engagement with the notch.

9. In a typewriter, the combination with a movable rack bar, of a frame with respect to which the bar is movable, a margin stop adjustable on the bar having a lever pivoted thereto with a projecting contact arm, and a stop bracket fixed to the frame having an upturned end and sides connected to the end forming a pocket for receiving the end of the contact arm.

10. In a typewriter, the combination with a frame and a transversely movable rack bar, of a stop fixed on the frame and a releasable left-hand margin stop adjustable on the bar having a releasable lever pivoted on the left hand margin stop and having an abutment which normally engages the fixed stop on the frame and is movable out of the path of the fixed stop to permit writing in the left-hand margin without losing the adjustment of the margin stop.

11. A releasable typewriter stop consisting of a hollow body portion adapting the stop to be moved along a stop bar, an adjusting lever to hold the stop in any desired position, a spring to press the lever into engaging position, the body being formed on its bottom edge with an angular notch, pivots mounted in the sides of the body and a releasable lever carried by the pivots having a releasing arm extending upwardly from one of the pivots, having an engaging arm with an angular abutment portion extending beneath the body portion and adapted to engage in the angular notch of the body portion to limit the outward movement of this arm of the lever, and a spring disposed between the abutment arm and the body, tending to press it in engagement with the angular notch.
12. In a typewriter, the combination with a movable rack bar, of a frame with respect to which the bar is movable, a margin stop adjustable on the bar having a contact arm, and a stop bracket fixed to the frame comprising a flat strip with an upturned end
13. A typewriter margin stop comprising a body portion, and a spring pressed releasing lever pivoted to the body having an arm 30 extending therefrom and an abutment portion normally pressed by the spring against the body to communicate an impact of the arm directly to the body.
14. A fixed bracket for a typewriter margin stop consisting of a piece of flat material fixed flatly to the typewriter frame with an upturned end bent at right angles to the flat sides and sides bent upwardly, adjoining the bent end to form an integral end pocket 40 for engaging the margin stop.

In testimony whereof I have signed my name to this specification, in the presence of two subscribing witnesses, on this 16th day of October, A. D. 1914.

ALVAH C. ROEBUCK.
